UNITED STATES PATENT OFFICE

2,589,622

SELF-VENTING VALVE

John B. McCabe, Milwaukee, Wis., assignor to
 The Heil Co., Milwaukee, Wis., a corporation
 of Wisconsin

Application June 28, 1948, Serial No. 35,589

14 Claims. (Cl. 222—481.5)

1

This invention relates to improvements in self-venting valves and, more particularly, to self-venting valves for use on liquid transport tanks.

Present day liquid transport tanks usually employ conventional valves for use in draining the same, and in this type of tank a manhole is usually provided in the top as a venting means. This top manhole also serves the purpose of providing access to the interior for cleaning. Some venting means is necessary, because otherwise exhaustion of the liquid from the tank will so reduce the pressure therein as to result in collapse caused by the pressure of the atmosphere on the exterior thereof.

The use of top manholes is unsafe because access thereto requires that the operator climb up on the tank. In addition, top manholes are objectionable from a sanitary standpoint when the tank is used for transporting a food product such as milk, because foreign matter may drop into the tank when said manhole is opened and cause contamination.

It is therefore a general object of the invention to provide a self-venting valve which eliminates the necessity of using a top manhole.

A further object of the invention is to provide a self-venting valve which may be operated from the ground level and which thereby eliminates the need for the operator to climb up on the tank before and after a draining or filling operation.

A further object of the invention is to provide a valve of the class described which permits the elimination of the top manhole and thereby permits the use of a manhole in the head or end of the tank for cleaning purposes.

A further object of the invention is to provide a valve which may be used to either empty or fill the tank with which it is in communication and which allows free egress or ingress of air during said filling or emptying operations.

A further more specific object of the invention is to provide a valve adapted to be mounted in the end of a tank and which has associated therewith a vent conduit extending to the upper portion of the interior of the tank.

A further object of the invention is to provide a valve of the class described having means associated therewith for draining the vent conduit prior to opening of the valve to thereby permit drainage of the tank.

A further object of the invention is to provide a valve of the class described which is sturdy in construction, which is easily disassembled and cleaned, and which is otherwise well adapted for the purposes described.

2

With these and other objects in view, the invention consists of the improved self-venting valve, and all its parts and combinations, as set forth in the claims, and all equivalents thereof.

5 A clear conception of the construction and operation of the improved valve will be had by reference to the drawings accompanying and forming a part of this application, wherein is illustrated one complete embodiment of the preferred form of the invention, and wherein the same reference numerals indicate the same parts in all of the views:

Fig. 1 is a longitudinal fragmentary vertical sectional view taken through the rear portion of 15 a tank to which the improved valve is connected, showing the valve in closed position, a portion of Fig. 1 being indicated by the line 1—1 in Fig. 4.

Fig. 2 is a view similar to Fig. 1 but showing the 20 valve in position to permit drainage of the venting conduit;

Fig. 3 is a view similar to Figs. 1 and 2, but showing the valve in position for draining or filling the tank while simultaneously venting said tank;

25 Fig. 4 is a fragmentary end view of the tank and valve looking from the rear; and

Fig. 5 is a transverse vertical sectional view taken along the line 5—5 of Fig. 1.

Referring more particularly to Fig. 1, of the 30 drawing, the numeral 10 indicates a substantially horizontally extending cylindrical tank, such as a truck tank or trailerized tank, having an end portion or crown 11. The crown 11 is formed with a flanged drain opening 12 in its lower portion.

35 Connected to the flanged opening 12 by means of suitable screws 13 is the flange 14 of a tubular housing 15. A suitable gasket 16 of rubber or other material is preferably interposed between the flanges 12 and 14. The housing 15 is formed on its outer end with suitable external threading 17, and projecting downwardly from a side portion thereof is a tubular extension or outlet pipe 18 which is formed at its lower end with external threading 19. The housing 15 is preferably 40 formed with an interior annular bevelled seat 20 adjacent that end which has the external threads 17.

Positioned over the outer end of the housing 15 in the preferred form of the invention is a 45 circular plate 21 formed with a peripheral bevelled surface 22 which registers with the bevelled seat 20 of the housing 15. The plate 21 is formed with an axially outwardly projecting boss 23 which is formed with external threading 55 24. The plate 21 and the boss 23 are axially

bored as at 25, and the plate 21 is held in position against the end of the housing 15 by an annular collar member 26 which is formed with internal threading 26' for engagement with the threading 17 of the housing 15.

Threaded on the boss 23 is a cap or collar 27, from the outer surface of which projects a pair of oppositely disposed substantially parallel arms 28. The arms 28 at their outer ends project inwardly and merge into a centrally disposed hub 29. Adjacent the curved portions of the arms 28 a pair of oppositely disposed handles 30 project outwardly in a diametrical direction. The cap or collar 27 is preferably axially apertured as at 31 to a size slightly less than that of the bore 25, and the hub 29 is centrally apertured as at 32 to a size slightly less than that of the aperture 31. The structure just described is usually termed a bonnet in its entirety.

An elongated tubular valve stem 33 is axially positioned within the housing 15 in the bore 25 and in the aperture 31. The stem 33 is formed at its outer end with a portion of reduced outer diameter 34 which is substantially the same size as that of the aperture 31 in the cap 27. The outer diameter of the remainder of the stem 33 is substantially equal to the diameter of the bore 25. Formed on an intermediate portion of the exterior of the stem 33 is a circular flange forming a poppet valve 35 which has an outer diameter substantially equal to the inner diameter of the housing 15. When the device is arranged in the position shown in Fig. 1, peripheral portions of the inner surface of the poppet valve 35 are seated on an annular shoulder 36 formed in the interior of the member 15.

Extending inwardly from the outer end of the stem 33 is a portion of enlarged inner diameter 37 which terminates in a bevelled annular seat 38. A cylindrical plunger 39 having an outside diameter substantially equal to the diameter of the portion 37 is adapted to be slidably positioned in the portion 37 of the stem 33 and is formed at its inner end with a bevelled annular surface 40 which is adapted to register with the bevelled seat 38 of the stem 33. The plunger 39 is formed adjacent its outer end with a portion of reduced outer diameter substantially equal to the bore 32 in the hub 29 which reduced portion extends through said hub. The plunger 39 extends beyond the hub 29 a sufficient distance for the reception of a snap key 41 on a portion of further reduced diameter 42. It is apparent that the plunger 39 is connected for axial movement with the hub 29 and the cap 27.

Positioned around the plunger 39 between the hub 29 and the outer end of the stem 33 is a helical spring 43 which is in compressed condition when the device is arranged in the position shown in Fig. 1. The stem 33 is formed with an aperture 44 through the wall thereof which is spaced slightly outwardly from the bevelled seat 38. When the plunger 39 is in the position shown in Fig. 1, the aperture 44 is interiorly closed off, and the plunger 39 is firmly seated on the seat 38 of the stem 33.

The inner end of the stem 33 projects into the tank 10 as shown in Fig. 1. By means of a suitable, preferably easily disconnectable, elbow 45, the inner end of the stem 33 communicates with a vertically extending vent conduit 46. The conduit 46 extends upwardly through a collar 47 formed with an annular flange 48 to within a short distance from the top of the interior of the tank 10.

A channel member 49 is preferably connected at one end to an upper portion of the tank head 11 and extends horizontally forward. The channel 49 at its forward end preferably extends angularly upwardly, as at 50, and is connected to the top of the tank as at 51. The web of the channel 49 is formed with a longitudinal slot 53 which is adapted to slidably receive the collar 47, and the flange 48 of the collar 47 is adapted to rest upon the upper surface of the channel 49, as is clearly shown in Fig. 5.

Operation

When the tank 10 is substantially full, the valve mechanism is normally in the position shown in Fig. 1. In transit, a certain amount of the liquid in the tank 10 will splash into the vent conduit 46. When it is desired to empty the tank 10, or discharge therefrom, the first step in the operation is to unscrew the cap 27 from the boss 23 by means of the handles 30. Upon disengagement of the cap 27 from the threads 24 of the boss 23, the spring 43, which had previously been in compressed condition, expands axially to move the cap 27 and the plunger 39 axially outwardly to the position shown in Fig. 2. This outward movement brings the plunger 39 off the seat 38 and uncovers the aperture 44, thereby creating communication between the interior of the stem 33, which is connected with the vent conduit 46, and the interior of the housing 15, the latter having the outlet pipe 18. With the valve mechanism in this position, any liquid which has splashed into the vent conduit 46 during transit is permitted to flow out the aperture 44 in the stem 33, into the interior of the housing 15 and out of the outlet pipe 18. Because of the location of the aperture 44 in the position shown, all of the milk which has splashed into the conduit 46 during transit is directed into the outlet pipe 18 at this stage, rather than being lost and possibly spattered on the operator. This would probably be the case if, in Fig. 2, the aperture 44 were positioned outwardly of the hub 23 and the plunger 39 were shortened accordingly.

It will be noted that when the cap 27 is in the position shown in Fig. 2, its outer surface adjacent the bore 31 is in engagement with a shoulder 52 which is formed on the exterior of the stem 33 by the portion of reduced diameter 34.

After all of the liquid has drained out of the conduit 46 and out of the stem 33, the mechanism being arranged as shown in Fig. 2, then the handles 30 of the cap 27 are grasped by the operator and pulled axially outwardly to bring the mechanism into the position shown in Fig. 3. It will be noted that the stem 33 has now been slid outwardly, and along with it the upstanding vent conduit 46. In the position of Fig. 3, the poppet valve 35 has been drawn outwardly off of the annular seat 36 to a position outwardly of the outlet pipe 18. The liquid in the tank 10 is now permitted to pass out through the interior of the housing 15 and out through the outlet pipe 18.

In the position of Fig. 3, the aperture 44 is positioned outwardly of the boss 23 and provides a port for permitting air to be admitted into the tank 10 via the interior of the stem 33, the connection 45, and the vent conduit 46. The liquid in the tank 10 will flow freely out the outlet pipe 18 due to the fact that adequate venting of the tank is provided, as above described.

It is obvious that the improved valve mechanism when arranged as shown in Fig. 3 may be used equally well for either draining the tank 10

or for filling the same. During a filling operation, the vent conduit 46 will provide means for egress of air from the tank, rather than a means for ingress of air thereto as is the case in a draining operation.

It will be noted that the improved valve construction entirely eliminates the necessity of using a manhole for venting purposes, and therefore permits the cleaning manhole (not shown) to be positioned in a head 11 of the tank 10. By eliminating top manholes, not only is the danger of climbing accidents eliminated, but, in addition, there is no longer any possibility of contamination of liquid, such as milk, in the tank 10 due to the entrance of foreign matter through an open top manhole.

The improved valve construction may be quickly and easily operated and may be quickly and easily disassembled and cleaned. Because of these features, the improved valve is particularly well adapted for use in tanks in which food products such as milk are transported.

In order to make it possible to readily disassemble the cap 28 from the stem 33, the hole 31 communicates with an enlargement 31'. Thus, when the spring clip 41 is removed from the plunger 39, the plunger may be pushed into the stem 33 far enough to permit transverse movement of the cap 28, after it is unthreaded, to a point where the enlargement 31' may be slipped over the shoulder 52. Thus, whenever cleaning is necessary, disassembly may be readily accomplished.

Various changes and modifications may be made without departing from the spirit of the invention, and all of such changes are contemplated, as may come within the scope of the claims.

What I claim is:

1. A self-venting liquid valve comprising a housing adapted to be attached to a tank and having a tubular portion in communication with the interior thereof, said tubular portion of said housing being formed with a valve seat, a tubular stem mounted for axial movement relative to said housing, said stem having a poppet valve thereon which is adapted to coact with said valve seat, and having its inner end projecting into said tank, a vent conduit in said tank to which said stem is connected, said tubular stem also being formed with an internal annular shoulder to provide an annular seat, and said stem being also formed with an aperture in a wall portion thereof outwardly of said annular seat, a plunger slidably positioned in the outer end of said stem and adapted to have its inner end coact with said annular seat for closing off the interior of said stem, and a cap mounted on said stem and having a portion thereof connected to said plunger, said cap being threadedly engageable with said housing to releasably hold said plunger and said poppet valve in closed position.

2. A self-venting liquid valve comprising a housing adapted to be attached to a tank and having a tubular portion in communication with the interior thereof, said tubular portion of said housing being formed with a valve seat, a tubular stem mounted for axial movement relative to said housing, said stem having a poppet valve thereon which is adapted to coact with said valve seat, and having its inner end projecting into said tank, a vent conduit in said tank to which said stem is connected, said tubular stem also being formed with an internal annular shoulder to provide an annular seat, and said

stem being also formed with an aperture in a wall portion thereof outwardly of said annular seat, a plunger slidably positioned in the outer end of said stem and adapted to have its inner end coact with said annular seat for closing off the interior of said stem, a cap mounted on said stem and having a portion thereof connected to said plunger, and means for retaining said cap on said stem while permitting limited axial movement of said cap relative to said stem, said cap being threadedly engageable with said housing to releasably hold said plunger and said poppet valve in closed position.

3. A self-venting liquid valve comprising a fitting adapted to be attached to a tank and having a tubular portion in communication with the interior thereof, said tubular portion of said fitting being formed with a valve seat, a tubular stem mounted for movement relative to said fitting, said stem having a valve thereon which is adapted to coact with said valve seat, said tubular stem being formed near one end with a vent opening and having its opposite end projecting into said tank, a vent conduit in said tank to which said stem is connected, said tubular stem also being formed with an internal annular shoulder to provide an annular seat inwardly of said vent opening, a plunger slidably positioned in the outer end of said stem and adapted to have its inner end coact with said annular seat for closing off the interior of said stem, a cap mounted on said stem for limited axial movement and having a portion thereof connected to said plunger, said cap being threadedly engageable with said housing to releasably hold said plunger and said valve in closed position, and spring means normally urging said plunger and said cap outwardly relative to said stem, whereby upon disengagement of said cap from said housing said plunger will be drawn outwardly off its seat to a position outwardly of said vent opening.

4. A self-venting liquid valve comprising a housing adapted to be attached to a tank and having a tubular portion in communication with the interior thereof, said tubular portion of said housing being formed with a valve seat, a tubular stem mounted for axial movement relative to said housing, said stem having a poppet valve thereon which is adapted to coact with said valve seat, and having its inner end projecting into said tank, a vent conduit in said tank to which said stem is connected, said tubular stem also being formed with an internal annular shoulder to provide an annular seat, and said stem being also formed with an aperture in a wall portion thereof outwardly of said annular seat, a plunger slidably positioned in the outer end of said stem and adapted to have its inner end coact with said annular seat for closing off the interior of said stem, a cap mounted on said stem for limited axial movement and having a spaced hub portion connected to said plunger, said cap being threadedly engageable with said housing to releasably hold said plunger and said valve in closed position, and spring means associated with said stem and said hub for normally urging said hub outwardly relative to said stem, whereby upon disengagement of said cap from said housing said plunger will be drawn outwardly off its seat to a position outwardly of said aperture.

5. A self-venting liquid valve comprising a housing adapted to be attached to a tank and having a tubular portion in communication with

the interior thereof, said tubular portion of said housing being formed with a valve seat, a tubular stem mounted for axial movement relative to said housing, said stem having a poppet valve thereon which is adapted to coact with said valve seat, and having its inner end projecting into said tank, a vent conduit in said tank to which said stem is connected, said tubular stem also being formed with an internal annular shoulder to provide an annular seat, and said stem being also formed with an aperture in a wall portion thereof outwardly of said annular seat, a plunger slidably positioned in the outer end of said stem and adapted to have its inner end coact with said annular seat for closing off the interior of said stem, a cap mounted on said stem and having a hub portion spaced outwardly therefrom and connected to said plunger, means for retaining said cap on said stem while permitting limited axial movement of said cap relative to said stem, said cap being threadedly engageable with said housing to releasably hold said plunger and said poppet valve in closed position, and a helical spring positioned around said plunger and between said hub and the outer end of said stem for normally urging said hub outwardly relative to said stem, whereby upon disengagement of said cap from said housing said plunger will be drawn outwardly off its seat to a position outwardly of said aperture.

6. A self-venting liquid valve comprising: a tubular fitting having an open end, said fitting being adapted to be attached to a tank with the open end thereof in communication with the interior of said tank, said fitting being formed with an internal valve seat and with an unobstructed discharge opening outwardly of said valve seat; a movably mounted tubular stem projecting through a wall portion of said fitting and having a portion within said fitting provided with a valve which is adapted to coact with said valve seat, said stem being formed with a vent opening which is so located that it is positioned within said fitting for communication with said fitting discharge opening when the valve is closed, and is positioned externally of said fitting wall portion when said valve is open; a vent conduit within said tank connected to said stem inwardly of said valve, and means for controlling said vent opening.

7. A self-venting liquid valve comprising: a tubular fitting having an open end, said fitting being adapted to be attached to a tank with the open end thereof in communication with the interior of said tank, said fitting being formed with an internal valve seat and with an unobstructed discharge opening outwardly of said valve seat; an axially movably mounted tubular stem projecting through a wall portion of said fitting and having a portion extending axially within said fitting provided with a valve which is adapted to coact with said valve seat, said stem being formed with a vent opening which is so located that it is positioned within said fitting for communication with said fitting discharge opening when the valve is closed, and is positioned externally of said fitting wall portion when said valve is open; a vent conduit within said tank connected to said stem inwardly of said valve, and means for controlling said vent opening.

8. A self-venting liquid valve comprising: a tubular fitting having an open end, said fitting

being adapted to be attached to a tank with the open end thereof in communication with the interior of said tank, said fitting being formed with an internal valve seat and with an unobstructed discharge opening outwardly of said valve seat; a movably mounted tubular stem projecting through a wall portion of said fitting and having a portion within said fitting provided with a valve which is adapted to coact with said valve seat, said stem being formed with a vent opening which is so located that it is positioned within said fitting for communication with said fitting discharge opening when the valve is closed and is positioned externally of said fitting wall portion when said valve is open; a vent conduit within said tank connected to said stem inwardly of said valve, and means normally closing said vent opening, said means being movable to open said vent while the latter is within the fitting and in communication with said fitting discharge opening.

9. A self-venting liquid valve comprising: a tubular fitting having an open end, said fitting being adapted to be attached to a tank with the open end thereof in communication with the interior of said tank, said fitting being formed with an internal valve seat and with an unobstructed discharge opening outwardly of said valve seat; a movably mounted tubular stem projecting through a wall portion of said fitting and having a portion within said fitting provided with a valve which is adapted to coact with said valve seat, said stem being formed with a vent opening which is so located that it is positioned within said fitting for communication with said fitting discharge opening when the valve is closed and is positioned externally of said fitting wall portion when said valve is open; a vent conduit within said tank connected to said stem inwardly of said valve, and a plunger slidably positioned in the bore of said stem normally closing said vent opening, said plunger being slidably outwardly to open said vent when the latter is within the fitting and in communication with said fitting discharge opening.

10. A self-venting liquid valve comprising: a tubular fitting having a closed end and an open end, said fitting being adapted to be attached to a tank with the open end thereof in communication with the interior of said tank, said fitting being formed with a coaxial internal valve seat and with an unobstructed discharge opening outwardly of said valve seat; an axially movably tubular stem projecting axially of said fitting through said fitting end wall and having a portion within said fitting provided with a poppet valve which is adapted to coact with said valve seat, said stem being formed with a vent opening which is so located that it is positioned within said fitting for communication with said fitting discharge opening when the valve is closed and is positioned externally of said fitting end wall when said valve is open; a vent conduit within said tank connected to said stem inwardly of said valve, and means normally closing said vent opening, said means being movable to open said vent while the latter is within the fitting and hence in communication with said fitting discharge opening.

11. A self-venting liquid valve comprising: a tubular fitting having a closed end and an open end, said fitting being adapted to be attached to a tank with the open end thereof in communication with the interior of said tank, said fitting being formed with a coaxial internal valve seat

and with an unobstructed discharge opening outwardly of said valve seat; an axially movable tubular stem projecting axially of said fitting through said fitting end wall and having a portion within said fitting provided with a poppet valve which is adapted to coact with said valve seat, said stem being formed with a vent opening which is so located that it is positioned within said fitting for communication with said fitting discharge opening when the valve is closed and is positioned externally of said fitting end wall when said valve is open; a vent conduit within said tank connected to said stem inwardly of said valve; a plunger slidably positioned in the bore of said stem and normally closing said vent; and means including a manually operable bonnet coacting with said fitting for releasably holding said plunger and said poppet valve in closed position.

12. A self-venting liquid valve comprising: a tubular fitting having an open end, said fitting being adapted to be attached to a tank with the open end thereof in communication with the interior of said tank, said fitting being formed with an internal valve seat and with an unobstructed discharge opening outwardly of said valve seat; a movably mounted tubular stem projecting through a wall portion of said fitting and having a portion within said fitting provided with a valve which is adapted to coact with said valve seat, said stem being formed with a vent opening which is so located that it is positioned within said fitting for communication with said fitting discharge opening when the valve is closed and is positioned externally of said fitting wall portion when said valve is open; a vent conduit within said tank connected to said stem inwardly of said valve; a plunger slidably positioned in the bore of said stem and normally closing said vent opening; and a manually operable bonnet on the outer end of said stem having a portion connected to said plunger, said bonnet being threadedly engageable with the fitting to releasably hold said plunger and poppet valve in closed position.

13. A self-venting liquid valve comprising: a tubular fitting having an open end, said fitting being adapted to be attached to a tank with the open end thereof in communication with the interior of said tank, said fitting being formed with an internal valve seat and with an unobstructed discharge opening outwardly of said valve seat; a movably mounted tubular stem projecting through a wall portion of said fitting and having a portion within said fitting provided with a valve which is adapted to coact with said valve seat, said stem being formed with a vent opening

- which is so located that it is positioned within said fitting for communication with said fitting discharge opening when the valve is closed and is positioned externally of said fitting wall portion when said valve is open; a vent conduit within said tank connected to said stem inwardly of said valve; a plunger slidably positioned in the bore of said stem, there being an annular seat formed on the interior of said stem inwardly of said vent opening and forming a valve seat with which the inner end of said plunger is adapted to coact to close off the interior of said stem; and means for releasably holding said valve and said plunger against their respective seats.
- 15 14. A self-venting liquid valve comprising: a tubular fitting having an open end, said fitting being adapted to be attached to a tank with the open end thereof in communication with the interior of said tank, said fitting being formed with an internal valve seat and with an unobstructed discharge opening outwardly of said valve seat; a movably mounted tubular stem projecting through a wall portion of said fitting and having a portion within said fitting provided with a valve
- 20 15. 25. which is adapted to coact with said valve seat, said stem being formed with a vent opening which is so located that it is positioned within said fitting for communication with said fitting discharge opening when the valve is closed and is positioned externally of said fitting wall portion when said valve is open; a vent conduit within said tank connected to said stem inwardly of said valve; a plunger slidably positioned in the bore of said stem, there being an annular seat formed on the interior of said stem inwardly of said vent opening and forming a valve seat with which the inner end of said plunger is adapted to coact to close off the interior of said stem; and means including a cap threadedly engageable
- 30 35. 40. with said fitting for releasably holding said valve and said plunger against their respective seats.
